UNITED STATES PATENT OFFICE.

JEAN F. WEBB, JR., OF NEW YORK, N. Y., ASSIGNOR TO INTERNATIONAL SIGNAL COMPANY, OF NEW YORK, N. Y.

TRAIN-STOPPING MECHANISM.

1,185,031.

Specification of Letters Patent.

Patented May 30, 1916.

Application filed August 22, 1914, Serial No. 358,094. Renewed October 28, 1915. Serial No. 58,069.

To all whom it may concern:

Be it known that I, JEAN F. WEBB, Jr., residing at New York, in the county of New York and State of New York, have invented 5 certain new and useful Improvements in Train-Stopping Mechanism, of which the following is a specification.

In the art of train signal and control there has heretofore been devised, apparatus, which, when brought into action, will 10 effectually operate warning signals in the engineer's cab, set the air brakes, or close the throttle. Those systems which operate to set the air brakes may be sub-divided into 15 two broad classes, viz: the electrical or electromagnetic type:—those in which the air valve is operated indirectly through the influence of electrooperative mechanism on the train, working usually in connection 20 with electrical sub circuits and contact makers located along the right of way; the second type may be called the mechanical type:—those in which the valve or other device on the train is actuated by a mechanical 25 instrumentality that engages a stop, ramp, or other device along the right of way.

In the mechanical class of train stops there has heretofore been devised an apparatus 30 whereby the air valve is always opened whenever the track obstacle (a fixed ramp) is encountered and if the right of way is clear, the valve is again and immediately closed, ere the brakes can be set, 35 to thereby suppress or counter-act the opening action of the valve of the air brakes, but if the right of way be not clear, then the suppression does not occur. An example of such a system may be found in my application 40 filed January 18, 1912, Serial Number 671859.

A signaling apparatus on a somewhat similar principle *i. e.* where the signal is always set and suppressed if the line is 45 clear, is also known in the above mentioned electrical type of apparatus, see for instance, the patent to Jacobs *et al.* Number 833603, of October 16, 1906. In the Jacobs *et al.* apparatus, the acting and reacting 50 mechanism are electromechanically controlled, one part including a complete train circuit and the other part including a partial train carried circuit and a partial road-way circuit, there being a contact member 55 provided to control the switch on the train

that governs the wholly train carried circuit and also acts as the contact member to complete the connection between the train carried partial circuit and the road-way partial circuit.

My present invention relates to what might be termed a third type, viz., one in which the apparatus is partly mechanical and partly electrooperative:—one in which one complete set of operations on the air 60 brake valve is performed entirely by mechanical means and in which the suppression action is performed by electromechanical means.

In the present invention the air valve is 70 always opened by a purely mechanical instrumentality whenever the train apparatus engages the track fixture, the mechanical mechanism being rendered non-operative, however, if the right of way is clear, 75 by electromechanical devices which are operated by a partial train circuit and a controlled partial track circuit of which the track fixture and that part of the train apparatus which engages it are portions.

Generically the present invention provides an air valve on the train which is connectible with the train pipe of the air brake system, the valve being designed to be opened by a plunger on the train whenever the 80 plunger mechanically engages a track ramp or fixture, the plunger and the valve being mechanically related so as to be normally in a position to operate, the plunger including a part adapted to be swung out of 85 its normal path of action by an electrooperative device whenever the plunger makes electrical contact with the track ramp or fixture to close the train carried partial circuit whenever a track partial circuit that 90 includes the rails and ramp is closed and thereby prevent the setting of the brakes when the plunger moves under the influence of the mechanical contact between it and the ramp.

In its more subordinate nature, the invention includes those novel details of construction, combination, and arrangement of parts, all of which will be first fully described, then be specifically pointed out in 105 the appended claims and illustrated in the accompanying drawings, in which:—

Figure 1 is a vertical section taken on the line 1—1 of Fig. 4. Fig. 2 is a horizontal section on the line 2—2 of Fig. 1. Fig. 3 is 110

a vertical section on the line 3—3 of Fig. 2, showing the position of the parts when the plunger has been mechanically raised and the electromagnet has been energized through the closing of the train carried circuit via the electrical contact between the plunger and the ramp. Fig. 4 is a vertical section on the line 4—4 of Fig. 1. Fig. 5 is a detail section on the line 5—5 of Fig. 1. Fig. 6 is an enlarged detail vertical section of the plunger that operates the valve. Fig. 7 is an elevation of the plunger head showing the hinged section of the plunger. Fig. 8 is a top plan view of the parts shown in Fig. 7. Fig. 9 is a diagrammatic view showing the connections between the air valve mechanism and the air brake system of the train. Fig. 10 is a diagrammatic view of the electrical circuits. Fig. 11 is a vertical cross section on the line 11—11 of Fig. 12 showing the construction of the valve mechanism *per se*. Fig. 12 is a front elevation of the valve mechanism, the cover being removed. Fig. 13 is a side elevation of the parts shown in Fig. 12. Figs. 14 and 15 are detail views of the valve members proper. Fig. 16 is a section on the line 16—16 of Fig. 2, showing the speed control resetting mechanism. Fig. 17 is a top plan view of the same. Fig. 18 is a section on the line 18—18 of Fig. 1. Fig. 19 is a view similar to Fig. 18, illustrating a modification of the plow or contact shoe.

In the drawings in which like numerals and letters of reference designate like parts in all of the figures, 1 represents the casing which is designed to be attached to any suitable part of the locomotive and insulated therefrom in any suitable way. The casing 1 is provided with a door or cover plate 2, through which access to the interior of the casing may be had. The casing may be provided with one or more plunger carriers 3 and 4, accordingly as one or more plungers are used. Each of the plunger carriers 3 and 4 is essentially of the same construction excepting that the front one is preferably provided with a suitable penetrating nose 154 to go through any obstruction that may be encountered. Each plunger carrier 3 or 4, as the case may be, is bored to receive the respective plunger 5. Each plunger 5 includes a stem portion 6, that has squared sides 7 to pass through a similarly shaped aperture in the guide plate 15, which is bolted down within the casing 1, the object being to prevent the plungers from turning on their longitudinal axes and confine motion to straight up and down reciprocation. Each plunger is provided with a pocket-like portion 8 to receive the coil spring 9 which continuously tends to press the plunger downwardly.

10 designates a bore which is provided in the rear or valve operating plunger (and

may or may not be provided in the front plunger, as desired) and this bore 10 is connected with a pipe 13 through a nipple 12 threaded into the plunger at 11. The pipe 13 is designed to connect with the air valve 70 as will be later explained. The stem 6 is threaded at its upper end as at 14 to receive the threaded member 16 which serves as a nut to abut the plate 15 and limit the downward movement of the plunger. The 75 threads of the nut are cut away as at 17 to admit of a key 18 that prevents the nut from unscrewing, the key 18 being secured by ears 19 and cotter pins 20. The nut or base 16 of the operating plunger has a rearwardly and upwardly directed ear 21 that is bored to receive a pivot pin 22, the pin 22 also passing through the ears 23 on the head 25 to hinge such head to the nut or base member 16. The head 25 has stops 26 to 85 limit its rearward movement and the pin 22 is held in place by cotters 24.

27 designates the abutment end of the head 25, which is designed to engage the nose 36 of the cam that is secured to the 90 valve shaft 32.

28 designates stiffening ribs on the inside of the head 27, and 29 represents a flange on the side of the head with which the roller 42 of the bell crank 40 is designed to engage. The flange 29 is provided with stiffening ribs 30 for the usual purpose and the head 25 is also braced by a cross bar 31 over the hinge joint to prevent the spreading of the ears 23.

32 represents the valve shaft or valve holding device which is designed for the purpose of retaining the valve proper in its closed position under normal conditions. The shaft 32 is mounted in bearings 33, and 34 designates the key by which the shaft and cam 35 are secured together. The cam 35 includes the main operating nose 36, hereinbefore referred to, and an arm 37 having a latch recess 38 to coöperate with the latch 39 that holds the shaft 32 in its normal position and prevents it from being jarred out of such position.

40 represents a deflecting lever which is fulcrumed at 41 and has a roller 42 on one of its arms to engage the flange 29 on the head 25. The other arm of the deflecting lever 40 is connected at 43 with the core 44 of the electromagnet 45, the core and magnet 45 being of any approved construction, 115 preferably, however, of the solenoid type. The electromagnet 45 is mounted at 46 within the casing 1. One terminal 47 of the magnetic winding is passed through an insulated bushing 48 to the outside of the 125 housing 1 and is connected to some metallic part of the train whereby to establish an electrical connection via the wheels, with the track rails. The other terminal 49 of the magnet winding is electrically connected to 130

some metallic part of the apparatus contained within the casing 1, as for instance to the nut head 16^a of the front plunger 5, when such is employed or if desired the electrical connection between 49 and the plungers may be made by connecting such connection with any of the parts carried by the casing 1.

The resetting mechanism consists of a rod 56 which has a head 50 that is provided with a plurality of projections 51, 52, 53. The projections 51 and 52 are spaced apart and coöperate with the arm 37, while the projections 52 and 53 are spaced apart and coöperate with the plate 55 that is secured to the guide 54 and retains the head 53 in the channelway of the guide.

57 is a spring which continuously tends to hold the projection 52 against the stop plate 55.

20 The rod 56 is adapted to be connected to another rod (not shown), which is designed to project into the engineer's cab so that the engineer may effect the resetting act, it being of course, understood that this rod will be electrically insulated from the rod 56 by any suitable insulated joint. The control of the resetting act is effected by a specially constructed speed governor device that 25 operates with the rod 56 to latch it from operation when the speed of the train is above a predetermined minimum.

60 is the main supporting housing for the speed controlled governor mechanism, the 30 purpose of which is, as before stated, to lock the rod 56 from operation whenever the speed of the train is above a predetermined minimum. The housing 60 may be provided with removable side plates 83 where- 35 by access to the interior may be had, and the housing is also provided with bearings 40 for the rod 56.

45 By reference, particularly to Figs. 1, 2 and 16, the construction of this mechanism will be best understood. 59 designates the threaded end of the rod 56 to which the engineer's operating rod (not shown) is designed to be secured. 62 is a bearing the cap 63 of which is fastened to the housing 50 60 and which supports the drive shaft 65 that extends to and is geared up in any suitable manner with a rotating part of the train (not shown) as for example, the front truck of the locomotive. The shaft 65 is 55 coupled at 66 to the governor shaft 67. The governor shaft 67 has collars 68 to prevent end-wise movement and it runs in ball-bear- 60 ings 69 carried by the frame or housing 60. 70 is a plug that is inserted into the bottom 65 of the housing 60 to close the same. A sleeve 71 is located on the shaft 67 and is adapted for longitudinal movement on the shaft under the influence of the centrifugal 65 governor balls 73. The balls 73 are pivot- ally mounted at 74 on a pin 72, which is car-

ried by the shaft 67 and passes through slots in the sleeve 71. The balls 73 have lugs 75 to which the links 76, that connect the balls with the lugs 77 of the sleeve 71, are fastened. 79 is the weighted latch member 70

which, in the preferred construction, is made in duplicate parts fastened together by suitable fastenings, and provided with bearings 80 to receive the guide pins 81 that are carried by the frame 60 and are held 75 from displacement by the cap 63. The latch member 79, as before stated, is made up of corresponding halves for the reason that should one of the latch lugs 82 become broken, it will only be necessary to turn the 80 latch 79 through a half circle, when the other lug may be brought into operative position to enter the slot 58 of the rod 56 and thereby avoid the necessity of replacing the latch with a new one. In practice the 85 weight of the latch member determines the speed required to effect the latching and unlatching functions. In order to adjust the latch mechanism for different speeds, additionally weighted latch members will be em- 90

ployed, the latch members being readily inter-changeable. The latch 79 is provided with an anti-friction bearing 78 by means of which it is connected with the sleeve 71 so that, as the sleeve is raised, the latch will be 95 elevated accordingly. The cap 63 may be provided with a casing projection 64 of the flexible tube type, and the shaft 65 may be of flexible type, if desired; the construction of the shaft 65 and the tube 64 being *per se*, 100 no part of the present invention. 84 designates the shoe which is of a peculiar construction. The shoe 84 is united with the plunger by a thin portion 87, that is de- 105 signed to break in the event of undue strain, so as not to ruin the plunger proper. The bore 10 of the rear plunger 5 (when two plungers are used) extends down through the connection 87 into the shoe 84. The purpose of this is that in the event of the breakage of 110 the plunger or shoe, the air brakes will be set by releasing the air in the bore 10. The shoe 84 is in the nature of a flat plate, the front face 85 of which is beveled up- 115 wardly and backwardly and preferably from the inner side toward the outer side, so as to form a knife or plow like member to shear off any snow and ice that may accumulate on the path through which the shoe moves and throw it to one side. The 120 outside of the shoe is also beveled vertically and inwardly as best indicated in Figs. 1 and 18 or the beveling may be double as is indicated in Fig. 19. Another feature of 125 the shoe is that the under face of it, is, pref- erably, not in a true horizontal plane, whereby the front edge of the shoe will be slightly elevated from contact with the ramp and thereby prevent the front sharp 130 knife-like edge of the shoe from being

dulled by contact with the ramp. I prefer to employ in addition to the operating plunger a front plunger which has for its principal purpose the clearing of the ramp and right of way from obstructions that would interfere with the operation of the operating plunger and when such front plunger is employed (see Fig. 1) the shoe may be attached by a threaded shank 88 that is held 10 from turning by a lug and pin connection 89 and 90, the pin being held in place in the lug by a cotter 91.

In Fig. 10, I have diagrammatically indicated the train carried partial circuit and 15 also a track partial circuit it being understood, however, that the track partial circuit which includes the rails 94 and the ramp 92 may be of any approved type, such as a block circuit or a semaphore controlled circuit or a simple switch controlled circuit as 20 desired. For purposes of illustration, the ramp sub-circuit is indicated simply with a battery and key, so that the circuit may be opened or closed at will. The train carried circuit includes the plunger 5 and the 25 wheels 95.

In Fig. 9, I have diagrammatically illustrated the connection between the main reservoir 96 and the train pipe 101. In this 30 figure, 97 designates the engineer's valve which is connected with the reservoir 96 by a pipe 106 and which is connected to the double heading valve 98 by a connection 105. The valve mechanism 107 of my apparatus is designed to be connected with the 35 double heading valve 98 through a connection 103 in which is interposed an insulated joint 99 (of train hose or other suitable material) and the valve mechanism 107 is also 40 designed for connection with the train pipe 101 by a pipe 102 which includes an insulating section 99. 100 represents the signal whistle that is connected with the valve mechanism 107 by connection 104, the latter 45 connection, also including an insulated section 99.

The improved valve mechanism which, *per se*, forms the subject matter of my application, Serial Number 843866, filed April 50 27, 1914, is best illustrated in Figs. 11 to 15 inclusive, and by reference to these figures, it will be observed that the valve mechanism includes the main or lower section 107, the relatively permanently held upper section 108, and the removable cover 109. The upper and lower sections 107 and 108 are provided with lugs 110 through which the fastening screws that secure the valve mechanism to the housing 1 may be passed. 55 The upper and lower sections are also provided with lugs 111 to receive the fastening screws 112 that hold the parts together. The upper section 108 is provided with a bearing post 113 to receive one of the bushings of the shaft 32, which shaft has its 60 65

end projected into the valve mechanism housing as best shown in Figs. 11 to 13 inclusive. The lower section of the valve mechanism housing includes two openings 114, one of which is adapted to be plugged 70 (see Fig. 12) and the other is adapted to receive the connection 102 that leads to the train pipe proper 101. It is also provided with a main entrance 115, into which the pipe connection 103 from the double heading valve 98 is tapped. In addition to the openings 114 and 115, two other openings 116 and 117 are provided, the opening 116 being the one into which the piping 13 is tapped to lead air to the bore of the plunger, while the other 117 is provided for the reception of the pipe 104 that delivers to the whistle 100, or other suitable signal.

The lower section of the valve mechanism incloses three distinct chambers 118, 119 and 120, the chamber 118 being what I shall, for convenience, call the main-reservoir-air-chamber, and the other chamber 120, I shall term the exhaust-air-chamber. It is understood that this terminology is used particularly for purposes of convenience and is not used in the sense of a limitation.

121 is a stuffing box plug that is threaded into the upper end of the lower section 107 to close the chamber 120 at its upper 95 extremity. The plug 121 is bored and provided with a gland 122 and a packing 123 to form an air tight joint where the stem 124 passes through the same. The stem 124 is reduced to receive the head 125 which is pinned to the end 126 of the stem and is provided with a fork 127, to straddle a suitable collar 128 that is pinned at 129 to the shaft 32 and thereby prevent lateral movement of the head 125. The head 125 is also 100 forked at 130 to straddle the cam 131 that is keyed to the shaft 32 and in the fork 130 there is located a roller 132 on a spindle 133 to engage the cam 131. The purpose of the cam 131 is to normally hold 105 the stem 124 depressed. At the lower end of the stem 124 and in the chamber 120 there is located a cup 134 which is formed with the stem 124 and has a vertically elongated opening 135 for the pin 136 which is carried by a second cup 137 that telescopes within the cup 134, while a spring 138 normally presses the cups apart.

139 is the valve which controls communication between the chambers 119 and 120. 120 This valve, under normal conditions, is held closed by the engagement of a pin 140, which it carries in a bore 141, with the end face of the cup 137. The valve 139 has a stem 142 which projects into the bore 143 125 of the tubular stem 144 of the main valve 145. The valve 145 controls communication between the chambers 118 and 119. The valves 145 and 139 are so arranged that when one is closed the other is opened, and 130

vice versa. The valve stems 144 and 142 are fastened together by a suitable cotter pin passed through the holes 146—147 and the valve 145 has its stem 144 guided in 5 the valve seat passages by lugs 148 and 149.

150 is a plug tapped into the bottom of the valve casing to close the bottom opening into the chamber 118. The plug 150 is half-cupped as at 151 to form a moisture 10 condensation receptacle and thereby prevent a surplus of water of condensation from accumulating in the chamber 118 and possibly freezing up the valve 145. The plug 150 has a stem 152 that projects up into close 15 proximity to the valve 145, and a spring 153 surrounds the stem 152 and continuously tends to seat the valve 145 and consequently unseat the valve 141.

In operation the speed controlled latch 20 member 79 is designed to cause a disengagement between the latch 82 and the notch 58 when the train is running below a predetermined speed, say below five miles an hour, so that the engineer may reset the air valve 25 from the cab in the event that it is acted upon when the train is running below the predetermined speed.

Assume that the track circuit is open and a train, disregarding the stop signal, at 30 tempts to pass the ramp 92, the front plunger 5, being the first to engage the ramp, will be elevated and effect an electrical contact with the ramp. Inasmuch, however, as the track circuit is open, this electrical contact will have no effect on the magnet 45 so that as the second shaft 86 rides upon the ramp, the rear plunger 5 will be elevated, thereby causing the abutment end 27 of the head 25 to engage the nose 36 of the cam 35 40 to turn the valve holding shaft to the dotted position shown in Fig. 1 and thereby cause the valve holding cam 131 to release the stem of the air valve which permits the air pressure in the chamber 118 to force the valve 143 upwardly against its seat and thereby unseat the valve 139. The air pressure within the train pipe 101 then is released via the chamber 119 into the chamber 120 and to atmosphere via the whistle 100, 50 thus setting the air brakes and bringing the train to a stand-still. If the speed of the train is below the predetermined minimum, as soon as the action has occurred, the engineer can immediately reset the valve to prevent stoppage of the train, but if the speed of the train exceeds the predetermined amount, then the latch 82 will be in engagement with the notch 58 and prevent movement of the rod 56 and consequently the 60 engineer cannot reset the valve until the speed of the train drops below the predetermined amount. When the shoes 84 engage the track ramp and the track circuit is closed (the safety position) then the electrical contact made between the shoes and the

ramp will cause the magnet 45 to be energized. This results in the rocking of the deflecting lever 40 to the position shown in Fig. 3 to thereby move the head 25 of the plunger out of its normal path or position, 70 so that when the rear plunger 5 is raised by the ramp, the abutment end 27 of the head 25 will not engage the nose 36, but pass by it and hence fail to operate the air valve.

From the foregoing description, taken in 75 connection with the accompanying drawings, it is thought the complete construction, operation and advantages of the invention will be clear to those skilled in the art.

What I claim is:

1. In a system of the class described, a train carried apparatus including an air valve, means holding said valve closed, a device for releasing said holding means to permit said valve to open, said releasing device including a rotatable shaft, a member on said shaft, and a plunger adapted to normally engage with said member when said plunger is raised to rotate said shaft, a tripping ramp coacting with the said plunger 90 to effect the action of the same, electro-mechanical means co-operative with said plunger for rendering the same non-operative, said electro-mechanical means including a train carried partial circuit which includes 95 the wheels of the train and said plunger, and a track partial circuit which includes the rails and said ramp.

2. In a system of the class described, a train carried apparatus including an air 100 valve, means holding said valve closed, a device for releasing said holding means to permit said valve to open, said releasing device including a rotatable shaft, a member on said shaft, and a plunger adapted to normally engage with said member when said plunger is raised to rotate said shaft, a tripping ramp coacting with the said plunger to effect the action of the same, electro-mechanical means co-operative with said plunger for rendering the same non-operative, said electro-mechanical means including a train carried partial circuit which includes 110 the wheels of the train and said plunger, and a track partial circuit which includes 115 the rails and said ramp, said plunger including a part adapted to be moved to a position to render the plunger action non-effective on said valve holding means, said electro-mechanical means effecting said 120 movement.

3. The combination with an air valve on a vehicle, of wholly mechanical means including a normally rectilineally reciprocable plunger on the vehicle for opening said 125 valve, electro-operative means on the vehicle to divert said plunger from its rectilineal path to prevent any action of said opening means on the valve at times, a stationary member along the path of travel for me- 130

- chanically operating said plunger, a train carried partial circuit including said plunger and said electrooperative means and the vehicle wheels, and a track partial circuit including said stationary member and the rails for controlling the action of said electrooperative means.
4. The combination with an air valve on a vehicle, a normally rectilineally reciprocable plunger, and a valve operating shaft including a member adapted to project into the normal path of travel of said plunger when raised to open said valve, a road-way ramp to actuate said plunger, and means causing said plunger to deviate from its normal path of travel to prevent its effective action on said shaft.
5. The combination with an air valve on a vehicle, a normally rectilineally reciprocable plunger, and a valve operating shaft including a member adapted to project into the normal path of travel of said plunger when raised to open said valve, a road-way ramp to actuate said plunger, and means causing said plunger to deviate from its normal path of travel to prevent its effective action on said shaft, said plunger including a hinged body and said last named means including electrooperative devices for moving said hinged body on said hinge as said plunger is raised by said ramp.
6. The combination with an air valve on a vehicle, a normally rectilineally reciprocable plunger and a valve operating shaft including a member adapted to project into the normal path of travel of said plunger when raised to open said valve, a road-way ramp to actuate said plunger, and means causing said plunger to deviate from its normal path of travel to prevent its effective action on said shaft, said plunger including a hinged body and said last named means including electrooperative devices for moving said hinged body on said hinge as said plunger is raised by said ramp, a vehicle carried partial circuit including said electrooperative devices and said plunger, and a road-way partial circuit including said ramp and means for opening and closing said road-way partial circuit.
7. In an apparatus of the character stated, a stopping valve, an operating shaft, a projection on said shaft, an operating plunger including a yieldable head to coöperate with said projection when said head and shaft are moved together as a unit for turning said shaft and means for causing said head to yield to deviate from the normal path of travel and move to a non-operative position.
8. In an apparatus of the character stated, a stopping valve, an operating shaft, a projection on said shaft, an operating plunger including a yieldable head to coöperate with said projection when said head and shaft are moved together as a unit for turning said
- shaft, means for causing said head to yield to deviate from the normal path of travel and move to a non-operative position, and means for re-setting said operating shaft to its initial position.
9. In an apparatus of the character stated, a stopping valve, an operating shaft, a projection on said shaft, an operating plunger including a yieldable head to coöperate with said projection in turning said shaft, means for moving said head to a non-operative position, means for re-setting said operating shaft to its initial position, and a speed controlled mechanism for governing the operation of said re-setting means.
10. In an apparatus of the class described, a valve mechanism connectible with the train pipe of an air brake system, a cam shaft including means coöoperative with said valve mechanism for holding said valve mechanism in the normal position and for releasing said valve mechanism when said shaft is turned, a multiple cam on said shaft, a reciprocating plunger adapted to engage with one element of said cam to turn said shaft in one direction, a track ramp for moving said plunger through its operative movement, mechanism coöoperating with said plunger for moving said plunger out of its path of operation at times, and a resetting device coöoperative with a second of said cam elements.
11. In an apparatus of the class described, a valve mechanism connectible with the train pipe of an air brake system, a cam shaft including means coöoperative with said valve mechanism for holding said valve mechanism in the normal position and for releasing said valve mechanism when said shaft is turned, a multiple cam on said shaft, a reciprocating plunger adapted to engage with one element of said cam to turn said shaft in one direction, a track ramp for moving said plunger through its operative movement, and mechanism coöperating with said plunger for moving said plunger out of its path of operation at times, a resetting device coöoperative with a second of said cam elements, and means including said track ramp and said plunger for controlling the operation of said coöperating mechanism.
12. In a system of the class described, a train carried apparatus including an air valve, means holding said valve closed, a device for releasing said holding means, said releasing device including a plunger having a main body portion and a shoe united to the body portion by a breakable connection, and a yieldable head on the body portion, a tripping ramp for actuating said plunger and electrooperative devices for causing said head to yield to thereby prevent the effective action of said releasing device.
13. In an apparatus of the class described,

- a train carried air valve, means holding said valve closed, a device for releasing said holding means and including a plunger having a yielding head to engage said holding means under normal operations of the plunger, means for engaging said yielding head to cause it to yield and thereby prevent operative connection of said plunger with said valve holding means, and means located along the right of way for actuating said plunger and said plunger head engaging means.
14. In an apparatus of the class described, a train carried air valve, means holding said valve closed, a device for releasing said holding means and including a plunger having a yielding head to engage said holding means under normal operations of the plunger, means for engaging said yielding head to cause it to yield and thereby prevent operative connection of said plunger with said valve holding means, and means located along the right of way for actuating said plunger, and said plunger head engaging means, said right-of-way located means including a tripping ramp.
15. In an apparatus of the class described, a train carried air valve, means holding said valve closed, a device for releasing said holding means and including a plunger having a yielding head to engage said holding means under normal operations of the plunger, means for engaging said yielding head to cause it to yield and thereby prevent operative connection of said plunger with said valve holding means, and means located along the right of way for actuating said plunger and said plunger head engaging means, said plunger head engaging means including a tripping ramp.
16. In a train stopping apparatus, a valve, a holding member therefor, and a plunger for moving said holding member; a ramp for moving said plunger; and a mechanism for preventing any action on said holding member through the movement of said plunger, said mechanism including a device to deflect said plunger, from said holding member.
17. In a train stopping mechanism; a train carried air valve, a valve holding member, a plunger for releasing said holding member, a ramp for moving said plunger into action, a device for directing said plunger away from said holding member and thereby prevent action of said plunger on said holding member, and means for operating said device.
18. In a train stopping mechanism; a train carried air valve, a valve holding member, a plunger for releasing said holding member, a ramp for moving said plunger into action, a device for directing said plunger away from said holding member and thereby prevent action of said plunger on said holding member, and controlled means for operating said device.
19. The combination with an air valve on a vehicle, a plunger, including a hinged portion, a valve operating shaft including a member adapted to project into the normal path of travel of said plunger when raised to open said valve, a road-way ramp to actuate said plunger, and means causing said plunger to deviate from its normal path of travel to prevent its effective action on said shaft.
